UNITED STATES PATENT OFFICE.

FRANK N. REEVES, OF NEWARK, NEW JERSEY, AND ALBEN E. LUNDELL, OF NEW YORK,
N. Y., ASSIGNEES, BY MESNE ASSIGNMENTS, TO WESTERN ELECTRIC COMPANY,
INCORPORATED, A CORPORATION OF NEW YORK.

AUTOMATIC TELEPHONE-EXCHANGE SYSTEM.

1,227,932.

Specification of Letters Patent. Patented May 29, 1917.

Application filed May 10, 1913. Serial No. 766,803.

To all whom it may concern:

Be it known that we, FRANK N. REEVES and ALBEN E. LUNDELL, citizens of the United States, residing at Newark, in the county of Essex and State of New Jersey, and at New York, in the county and State of New York, respectively, have invented a certain new and useful Improvement in Automatic Telephone-Exchange Systems, of which the following is a full, clear, concise, and exact description.

This invention relates to an automatic switching system and particularly to a telephone exchange system comprising one or more main offices and one or more sub-offices or satellites associated and connected therewith by trunk lines. In a multi-office satellite system there would be provided trunk lines leading from each main office to each other main office of the system and other trunk lines leading from each main office to its own satellites.

Such a system may have, for example, ten main offices, each main office with its satellites having a capacity of ten thousand lines, making the capacity of the whole system one-hundred thousand lines. The capacity of the satellites may be for instance one thousand subscribers' lines each, although the number obviously may vary according to what the requirements may be in practice. The subscribers' lines may terminate either in a satellite or directly in a main office.

The object of this invention is to economize in the use of trunk lines between the satellites and main offices without the necessity of variable manipulation of the subscribers' calling devices to discriminate between calls local to a satellite and calls requiring connection through a main office. To this end automatic discriminating means are provided which operate without the necessity of any knowledge on the part of the party manipulating the calling device, whether the called for subscriber is connected to the same satellite as the calling subscriber or to a main office or some other satellite of the exchange, the calling device being manipulated in the same manner for all connections desired and strictly in accordance with the substation number of the subscriber wanted.

The characteristic feature of this invention is, therefore, that it provides in an automatic satellite exchange system, means whereby a subscriber connected to a satellite may be called without any discriminating act at the calling device, wherever located in the exchange, to direct the connection and without extending the talking connection through an interoffice trunk where the calling and called subscribers' lines terminate in the same satellite.

Each of the subscribers' lines at a satellite is associated with a pair of trunk finder devices, one only of which is used in extending a call to a subscriber external to the satellite, both being used in making connection to called subscribers in the same satellite with the calling. In addition to the trunk finder just mentioned, each satellite is provided with a group of hundreds selectors and connectors through which the satellite subscribers are reached when a call originates at the same satellite therewith and also a group of connectors through which the subscribers at the satellite are reached when the call originates external to the satellite.

The invention will be more readily understood by reference to the accompanying drawings wherein—

Figure 1 is a diagrammatic illustration of the multi-office satellite exchange system embodying the invention, and Figs. 2, 3 and 4 when placed together with Fig. 3 above Fig. 2 and Fig. 4 at the right thereof, represent the circuits and apparatus involved in establishing connections between subscribers.

Fig. 2 represents a pair of trunk finders such as is associated with each subscriber's line at the satellite.

Fig. 3 represents a first selector at the main exchange and a trunk finder associated therewith, and

Fig. 4 represents a hundreds selector and a connector at the satellite and a called subscriber's line and substation apparatus.

In Fig. 1 of the drawings, D represents a main office connected by trunk lines 100 to other main offices A, B, C and E, it being understood that similar trunk lines would extend in such an exchange from each of said main offices to each other main office.

Associated with the main office A are satellites, A', A² and A³ and subscribers' stations a', a², and similarly associated with the main exchange B are satellites B', B² and B³ and subscribers' stations b', b², and the other main offices may have satellites C', C² and C³, E', E² and E³, etc., the satellites being represented by the circles and the subscribers' stations by the small squares.

- 10 Associated with the main office D, the confines of which are indicated by the dotted rectangle, are the satellites D' and D² and the subscribers' stations d' and d² which are located at the satellite D' and other subscribers' stations d³ and d⁴ connected directly to the main office. The main office D may include a number of series of switching mechanisms represented therein by a first selector 101 and a second selector 102, from which trunk lines would extend to the third selectors of other main exchanges and also a third selector 103 to which trunks from other main exchanges would extend and a final connector 104 through which subscribers, local to the main exchange D, would be reached by calling subscribers at other main exchanges. In addition to these series of switching devices, other series of switching devices are provided including the first selectors 101, trunk finders 105, hundreds selectors 106 and final connectors 107, through which all the subscribers at the main exchange D would be reached by calling subscribers at the satellite D'. Subscribers at the satellite D² would be reached by subscribers local to the main exchange D and by all subscribers at other main exchanges through a trunk line similar to the trunk line 114 leading from said third selector to the satellite D². A call originating at D' would be extended to a subscriber at D² by way of the first selector 101, trunk finder 105, third selector 106, a trunk line leading from 106 to D² and a final selector (corresponding to 115 at D') at the satellite D². While most of the switching devices are illustrated and have been referred to in the singular herein, it is obviously to be understood that a plurality or group of these switches will be provided unless otherwise described.

The apparatus at a satellite such as D', for instance, may include line switches 108 and 109, selectors 403, and connectors 410 previously referred to. The arrangement of the apparatus thus diagrammatically illustrated in Fig. 1 is such that the subscriber at station d', for example, may obtain a connection to the subscriber at station d² over a local circuit such as 112 which is wholly within the satellite, or he may obtain a connection to any other subscriber of the exchange system whose line does not terminate at the satellite D' through a trunk line such as 113 leading to the main office

D, from whence the connection may be extended in the usual manner according to the particular location of the subscriber wanted. If any subscriber other than those connected to the satellite D' desires connection with a subscriber at this satellite, the circuit would be completed by way of selectors such as 101, 102 and 103 (variously positioned according to the location of the calling subscriber) through a trunk line as 114 to a final connector 115 at the satellite D'.

At this point it is sufficient to say that if a subscriber at d' sends calling impulses in correspondence to the number of some other station at the same satellite therewith, the trunk finder 108 will first pick a trunk 113 leading to the main office D and if by means of vertical impulses the brushes of the selected selector 101 are brought to a certain level or group of contacts, the circuits at said switch will be so altered that the ensuing movement, instead of being the usual automatic trunk hunting operation, will be a directive movement and, if the next series of impulses is such as to place the brushes of said selector 101 on a particular group of contacts individual to the satellite D', a loop circuit will be completed, whereby the calling line will be automatically disconnected from the trunk finder 108 and connected to the trunk finder 109 which will automatically pick a connecting circuit as 112 leading to a hundreds selector 403. The succeeding series of impulses will now act in the usual manner to first pick a final connector of a certain group and then direct the brushes of this final connector to the terminals of the wanted subscriber.

Referring now to Figs. 2, 3 and 4 wherein the circuits and apparatus required for the establishment of a connection between a subscriber at d' Fig. 2 with a subscriber at d² Fig. 4 are diagrammatically illustrated, each subscriber's line, such as line 200, 201 of the calling station d', is provided at the substation with the usual telephone apparatus and a controlling device or interrupter 202, the purpose of which is to deliver the operating impulses by interrupting the circuit at the substation, and at the satellite exchange with a pair of trunk finders 108 and 109. The sides 200, 201 of the line extend uninterruptedly to the switch spring 205 and contact of spring 206 respectively of trunk finder 109. The side 200 of the line also extends through armature 207 and back contact of magnet 212', wire 214, back contact and armature 209 of magnet 212, winding 211 of magnet 212 and battery 213 to ground. The side 201 of the line correspondingly extends through armature 208 and back contact of electromagnet 212', wire 215, back contact 216 and armature 210 to ground. Continuations of the conductors 130

214 and 215 also extend to switch spring 229 and contact of spring 230, respectively, at trunk finder 108.

In addition to the branches from the sides 200 and 201 of the line, just recited, additional connections are provided through which the subscriber may be reached when called. The trunk finders, master switches, selector and connectors may comprise any 10 suitable mechanism, that shown diagrammatically in the drawings being similar to the apparatus disclosed in British Patent No. 26,301 of 1906. For more specific description of the selector and connector reference is made to United States Patents Nos. 815,321 and 815,176, respectively. The plunger 217 of the trunk finder, as well understood, always stands before a set of springs associated with an idle connecting circuit 20 and upon sufficient energization of the electromagnet 212 this plunger will be drawn forward, forcing the insulating ball 218 thereof between the innermost springs of 25 said set, whereby each of the four springs of the set is forced outwardly into engagement with its coöperating contact. The lead 219 associated with the innermost upper contact spring of the switch extends to the master switch bank whereby, through the actuation 30 of well known means, all the idle plungers of the group are moved to the next idle position. Normally, current is supplied to the lead 220, but during the interval when the plungers are in transit from one position of 35 rest to the next, this lead is interrupted, for instance at contact 222, so that no line finder mechanism can be actuated during this interval. As hereinbefore stated, calls local to the satellite will be extended by the trunk 40 finder 109 by means of a third selector 403 and a connector 410 to the called subscriber. As such apparatus is well known in the art, it need not be fully described here. The selector may be of the two movement type 45 wherein a series of steps is taken to select the desired group of connectors, and then automatically hunts for an idle connector of the group. Likewise the connector may be of the two movement type in which the brushes 50 are first stepped to a certain group of contacts and then are moved to the terminals of the wanted subscriber's line. In Fig. 3 is shown a first selector of any suitable type and a trunk finder associated therewith, the 55 function for which will hereinafter appear.

In Fig. 4 is shown the talking circuit conductor of the apparatus including the main switch contacts 405, 406 of the selector 403, and 407, 408 of the connector 410, also condensers 409 and 411, impedance coil relays 412, 413 connected in bridge of the talking circuit on each side of the condensers and through which talking current is supplied to the calling and called subscribers from the 65 battery 414. Associated with the selector

and connector switches 403 and 410 there would preferably be local test and holding contacts 417 and 418 respectively. The brush of the latter is adapted to be connected to ground at 419 when the connector is brought to rest on the terminals of a called line, the object of this being to create a busy test condition for other connector switches.

It will be understood that the line of the called subscriber will have associated with it 75 trunk finders such as shown in association with the line of the calling substation d' and that the connections to such apparatus will be made by the conductors 421 and 422 corresponding to the conductors 200 and 201 respectively of the calling subscriber's line. As further description of the apparatus employed is not believed to be necessary, the 80 operation of the system will now be described.

Let it be assumed that the subscriber at station d' is calling for the subscriber at station d^2 , these two stations being connected to the same satellite, and let it be further assumed that this satellite contains 90 a group of subscribers' lines numbered from 99000 to 99999, and that the number of the calling subscriber is 99321. The calling subscriber at station d' removes his receiver from the hook, thereby closing the line circuit through the winding 211 of magnet 212, the current flowing over the following path: from the live side of the battery 213, winding 211 of magnet 212, armature 209 and contact, wire 214, armature 207 and back 95 contact of electromagnet 212', side 200 of the line, substation apparatus, side 201 of the line, armature 208 and back contact, wire 215, contact 216 and armature 210 to ground. This partially energizes the 100 electromagnet 212 and the armature 221 alone is attracted. The attraction of this armature closes the circuit from battery through the normally closed contact 222, wire 220, windings 223, 224, contact and armature 105 221, contact 225 and armature 210 to ground. This results in the attraction of left armatures 209, 210 and 226 of electromagnet 212, and also the attraction of the right armature 227 which actuates the plunger 217 to 110 force the insulating knob 218 between the innermost contact springs, thus closing all the contacts now associated with this plunger. The armature 227 in pulling up engaged the contact 228, thus completing a 115 short circuit about the winding 223, whereby the electromagnet 212 is made slow to release. It will be noted that the attraction of armature 210 has broken the original energizing circuit for the windings 223 and 224, but on account of the short circuiting of the winding 223, the armature 227 is retained attracted until a holding circuit is completed. When the plunger entered the 120 set of springs, the sides of the subscriber's 125 130

line were extended by springs 229 and 230 and coöperating contacts through the wires 231 and 232 to the selector 101, shown in Fig. 3, thus completing an energizing circuit 5 for the line relay 301 as follows: from the live pole of battery 302, upper winding of relay 301, contact 303, side switch wiper 304, wire 231, contact and spring 229, wire 214, contact and armature 207, side 200 of 10 the line, substation apparatus, side 201 of the line, armature 208 and contact, wire 215, spring 230 and contact, wire 232, side switch wiper 305, contact 306, through the lower winding of relay 301 to ground. Upon the 15 energization of relay 301, circuit is completed for relay 307 from the live pole of grounded battery through winding of 307, front contact and armature of 301 to ground, whereupon relay 307 attracts both armatures. The upper armature completes a holding circuit for the electromagnet 212 as follows: from battery 233, winding 234 of electromagnet 212, switch spring 235 and contact, wire 236, armature and back contact of relay 312, upper armature and contact of relay 307 to ground, thus assuring 25 that the plunger of the trunk finder will be retained in operated position. The lower armature completes a circuit from battery 308 through side switch wiper 346 and contact 350, vertical magnet 309, private magnet relay 310, lower armature and front contact of 307, through resistance 311 to ground. 309 and 310 however are not energized due to the high resistance 311 in the circuit. The apparatus has now been prepared for the reception of the selective impulses which as before stated are caused by 35 interrupting the circuit at the substation.

40 Each interruption of the substation circuit will cause the deenergization of relay 301, the armature of which upon retraction will short circuit the resistance 311, causing the energization of the vertical magnet 309 and relay 310. As these interruptions are of comparatively brief duration and follow each other in quick succession, the relays 307 and 310 being slow acting will not release during the intervals in which they are 45 deprived of current. In accordance with the assumption that the substation to be selected was 99321, the first series of impulses would consist of ten interruptions of the substation circuit, causing the armature of relay 50 301 to be retracted ten times, resulting in ten energizations of the vertical magnet 309, thus raising the set of brushes of the selector to the tenth level. In the first selector 101, here shown, the movable contact 313 is 55 adapted to engage its upper contact stop in all positions of the selector brushes except when positioned at the level in which the terminals individual to the satellite are located, or the tenth level in the case assumed.

60 65 Thus the switch brushes having stopped in

position to traverse the terminals of the tenth level, the contact spring 313 will be depressed into engagement with its lower stop contact and upon the first step of the side switch the rotary magnet 314 will be substituted for the vertical magnet 309. The side switch is actuated by the private magnet 315 which upon energization of the relay 310 became energized by a circuit from battery, through contact 316, and armature 70 of relay 310 to ground. The private magnet, however, does not effect the movement of the side switch wipers upon energization, but is adapted to move all of the wipers of the side switch one step upon deenergization. 75 The circuit of the private magnet is interrupted when the armature of private magnet relay 310 falls back due to the prolonged inclusion of the resistance 311 in the circuit of relay 310 upon termination of the series 80 of impulses.

The apparatus is now in position for the reception of the second series of impulses which in the case assumed would be ten. Upon the reception of this series of impulses 90 the brushes of the selector will be stepped around to the tenth set of terminals in the tenth level which is the set individual to the satellite D'. The brushes 317, 318 and 319 of the selector will now be on the contacts 95 320, 321 and 322. The circuit from the contacts 320 and 321 will be open and will have no function at this time. The brush 319, however, completes through contact 322 a loop circuit which causes the energization 100 of relay 312 over the following circuit: from the live pole of battery through winding of relay 315, contacts 316 and 351, contact 352, side switch wiper 326, brush 319 and contact 322, winding of relay 312, upper armature and front contact of relay 307 to ground. The private magnet did not operate to move the side switch wipers to third position upon the termination of the ten thousands series of impulses as the contact 105 316 engaged contact 351 before ground was cut off at the armature of private magnet relay 310. Upon energization of relay 312 the high potential battery 327 is opposed to the battery 237 causing the polarized 110 relay 238 to become energized over the following path: from ground through battery 327, front contact and armature of relay 312, wire 236, contact and spring 235, winding of relay 238 and battery 237 to ground. 115 Relay 238 has not been previously energized as the battery 237 was of the wrong polarity and as the current from battery 233, being of substantially the same potential as 237, was ineffective. The battery 327 may have 120 a potential of 48 volts while the batteries 237 and 233 may each have a potential of 24 volts. Obviously, batteries of other potentials may be used if desired.

Upon the energization of relay 238 circuit 130

is momentarily completed for the winding 211' of relay 212' as follows: from battery 213', through winding 211', armature 209' and upper back contact, through contact 5 and armature of relay 238 to ground. This energizes the electromagnet 212' merely enough to attract the armature 221', thus completing a circuit for the windings 223' and 224' of electromagnet 212' from battery 10 through normally closed contact 222' and lead 220', windings 223' and 224', contact and armature 221', lower back contact and armature 209', upper contact of armature 209', armature and contact of relay 238 to 15 ground. Armatures 207, 208, 209' and 227' are thereupon attracted. Armature 227' causes the actuation of the plunger 217' of the satellite trunk finder 109, thus extending the sides 200, 201 of the subscriber's line to 20 the hundreds selector 403 of the satellite through the switch springs 205 and 206 respectively, and their coöperating contacts.

The attraction of armatures 207, 208 interrupted the circuit leading from the sub-25 station to the trunk finder 108 and thence to the selector 101 at the main exchange D. This causes the deenergization of the line relay 301. When the armature of relay 301 is retracted, the circuit of relay 307 is in-30 terrupted which releases its lower armature completing a circuit for the release magnet 328 from battery through said magnet, off normal contact 329, back contact and lower armature of relay 307, back contact and 35 armature of relay 301 to ground. Thus the selector 101 is immediately returned to its normal condition and is again ready to be selected by a trunk finder.

Branching from the sides 200 and 201 of 40 the line, as previously explained, are conductors leading to multipled contacts 239 and 240 of the connector switches through which the subscriber d' would be reached when called. Associated with the contacts 45 239 and 240 is a test contact 241. Upon the initiation of a call when the electromagnet 212 on the line finder 108 was energized, and the armature 226 attracted, ground was placed on the conductor leading 50 to the test contact 241 so the multipled terminals of the calling subscribers' lines would test busy. Upon the deenergization of the electromagnet 212 by the interruption of the holding circuit for the winding 234 when 55 the selector 101 returns to normal, as just explained, the armature 226 will be retracted, removing the ground at the front contact, but a ground through the back contact will be substituted therefor as will presently 60 be explained.

Upon the actuation of the plunger 217' ground was placed on the lead 219' to the master switch bank, whereby, as before described, the idle plungers of this group will 65 be moved to a position in front of the con-

tacts of an idle connecting circuit. By the actuation of the springs 205 and 206 of the trunk finder, the sides 200, 201 respectively of the line are extended to the hundreds selector 403 completing a circuit for the relay 400 as follows: battery, upper winding 70 of relay 400, side 242 of the connecting circuit, contact and spring 205, side 200 of the line, substation apparatus, side 201 of the line, contact and spring 206, side 243 of the 75 connecting circuit, lower winding of relay 400 to ground. Upon the energization of relay 400 a circuit is completed for relay 401 from battery through winding of 401, armature and front contact of 400, to ground. 80 Upon the attraction of the upper armature of relay 401, ground is placed on the test wire 244 of the connecting circuit. This serves to complete a circuit for the holding winding 234' of the electro-magnet 212, from 85 battery through winding 234', spring 245 and contact, test conductor 244 and upper armature and contact of 401 to ground. It also serves to place ground on the test terminals 241 through a circuit as follows: 90 from contact 241, armature 226 and back contact of electromagnet 212, contact and spring 245, test conductor 244, upper armature and front contact of relay 401 to ground. The attraction of the lower armature of relay 401 serves to complete a circuit from battery through vertical magnet 95 423 and private magnet relay 424 to the back contact of relay 400. The hundreds selector 403 is now in condition to receive the next 100 series of selective impulses.

As previously described, only so much of the hundreds selector and final connector is shown in Fig. 4 as is necessary to illustrate the principal signaling and talking circuits 105 to the called subscriber's station d' . When the trunk finder made connection with the trunk line conductors 242, 243 and 244, the relay 401 was energized and thus prepared the hundreds selector for operation in the 110 well known manner by the impulses which subsequently occur. In the case assumed four impulses would now be sent and the brushes of the selector would be raised to the fourth level when they would automatically hunt for an idle connector. The ensuing series of impulses (three and then two) would now cause the brushes of the connector first to be stepped up to the third level in which are found the terminals of 115 the called subscriber's line, and then upon the final series of impulses, the brushes would be rotated until they were in engagement with the second set of contacts of the line terminals of subscriber d' . When the 120 brushes made contact with the terminals of the called subscriber's line, ground was placed on the test conductor 423 through the grounded contact of the side switch wiper 425, thus assuring that no other connector 125

will stop on any of the multiple terminals of the line d^2 .

Any well known method may be employed for signaling the called subscriber and upon his response by lifting his receiver from its hook, a complete talking circuit will be established as follows: from transmitter at station d' , receiver, line 200, spring 205 and contact, 242, 405, 409, 407, 10 side 200' of called subscriber's line and substation apparatus at d^2 , side 201' of line, 408, 411, 406, 243, spring 206 and contact, side 201 of line, back to the starting point. The talking current will be supplied to the calling subscriber's transmitter from battery 414 through the windings of relay 412, and to the called subscriber's transmitter through the windings of relay 413, the talking circuit being interrupted to battery current between the connections of these relays to said conductor by condensers 409 and 411.

Upon the termination of the conversation, when the calling subscriber places his receiver upon the hook, the circuit for the relays 400 and 412 will be interrupted and the hundreds selector 403 and the connector 410 will then be returned to normal in the usual manner.

We will now assume a call in which after 30 the tenth level of the first selector 101 at the main exchange has been picked, a series of impulses other than ten are sent, thus stopping the brushes 317, 318, 319, for example, on contacts 330, 331, 332 respectively. Upon the termination of this series of impulses the side switch contacts will be moved to third position. The line of the calling subscriber will now be extended to one of the trunk finders 105. A circuit will 40 now be completed for the winding 335 of the electromagnet of the line finder 105 from battery through said winding, first left-hand armature and contact 336 thereof, contact 330, brush 317, 333, 304, 231, 229, 214, 45 207, 200, substation apparatus at d' , 201, 208, 215, 230, 232, 305, 334, 318, 331, upper back contact and armature 342, to ground. The armature 341 is attracted and a local circuit is now completed for windings 337 50 and 338 from battery 339, through normally closed contact 340, windings 338, 337, contact and armature 341, lower back contact and armature 342 to ground. The actuation of contact 343 serves to complete a holding circuit for the release magnet relay 307 thus holding open the circuit of release magnet 328. The circuit for the relay 307 is as follows: live pole of battery through 307, 323, 324, 325, 326, 319, 332 to 343 and ground. Relay 307 is made slow acting and consequently 60 did not release during the brief interval in which it was deprived of current. The energization of windings 337 and 338 of electromagnet 336 causes the attraction of 65 the right armature 344, thus actuating the

plunger 345 and extending the line of the calling subscriber in the usual manner to the third selector 106 (Fig. 1). As from this point the call would progress in the usual and well known manner, further description is thought to be unnecessary.

We will next assume that the first series of impulses had resulted in raising the brushes of the first selector 101 to a level other than the tenth, as before assumed. If the brushes are stopped on any level but the tenth, contact 313 would remain in engagement with the upper stop. Now upon termination of the first series of impulses, the side switch wipers will move to second position and a circuit will be completed from battery 308 through wiper 346 and contact 347, through the winding of the rotary magnet 314, spring 313 and upper contact, through the winding of guarding relay 348 and interrupter 349 to ground. The brushes of the first selector would then automatically hunt for an idle second selector 102 (Fig. 1). When the test brush 319 engaged the test contact associated with an idle second selector, this contact would not be connected to ground and the private magnet 315 would be deprived of current, thus causing the side switch contacts 304, 305, 326 and 346 to step to the third position. Side switch wiper 346 in moving to the third position will remove battery from the rotary magnet 314 and thus stop the selector brushes in engagement with contacts associated with an idle second selector. The side switch wipers 304 and 305 when moved on to the contacts 333 and 334 extended the line of the calling subscriber to the selected second selector through the brushes 317 and 318 in a well known manner. The side switch wiper 326 in engaging its contact 325 completed a holding circuit for the release magnet relay 307 from grounded battery through 307, 323, 324, 325, 326, 319, to ground at the second selector, thus retaining the release magnet relay energized. As the relay 307 is made slow acting, it did not release during the brief interval it was deprived of current.

As the operation of setting up the connection through the second selector 102, third selector 103 and final connector 104 would progress in the usual and well known manner, further description is thought to be unnecessary.

What is claimed is:

1. In an automatic telephone exchange system, a main office, a satellite office, inter-office trunk lines extending from said satellite to said main office, local trunk lines within said satellite, means for selecting an interoffice trunk upon the initiation of a call at said satellite, automatic switching mechanism for effecting connection between subscribers, controlling devices associated with

5 said satellite for governing said switching mechanism, and discriminating means at said main office operated under the control of said controlling devices when manipulated in accordance with the number of the wanted subscriber, for completing a connection over said interoffice trunk or for releasing said interoffice trunk and selecting a local trunk and effecting a connection over said 10 local trunk according to whether the wanted subscriber is located at an exchange exterior to said satellite or at said satellite.

15 2. In a telephone exchange system, a main office, a satellite office, trunk lines extending from said satellite to said main office and other trunk lines local to said satellite, a pair of trunk finders at said satellite, one for connecting the line of a calling subscriber at the satellite to an interoffice trunk and 20 the other for connecting the line of the calling subscriber to a local trunk, and means at said main office whereby the interoffice trunk finder is actuated upon the initiation of all calls at the satellite and whereby the 25 local trunk finder is actuated only when the calling and called subscribers are at the same satellite.

3. In a telephone exchange system, a main office, a satellite office, trunk lines extending 30 from said satellite to said main office and other trunk lines local to said satellite, automatic switches for effecting connection between subscribers, a pair of trunk finders at said satellite through one of which talking 35 connection is established from calling subscribers at the satellite to subscribers associated with the main office and through the other of which connection is established to subscribers at said satellite, controlling devices associated with said satellite for governing 40 said switches, and means at said main office operated under the control of said controlling devices when manipulated in accordance with the number of a wanted subscriber 45 for selecting the necessary line finder and completing a talking connection therethrough.

4. In a telephone exchange system, a main office, a satellite office, interoffice trunk lines 50 extending between said satellite and said main office and local trunk lines at said satellite, automatic switching mechanism for effecting connection between subscribers, said mechanism including a pair of trunk finders at said satellite for said interoffice and local trunk lines respectively, through 55 one of which trunk finders the line of the calling subscriber may be extended to subscribers at the main exchange and through 60 the other to subscribers at the satellite, controlling devices associated with said satellite for governing said switches, and means at 65 said main office operated under the control of said controlling devices when manipulated in accordance with the number of a

wanted subscriber for completing a connection through the required one or the other of said trunk finders according to whether the wanted subscriber is located at the same satellite with the calling subscriber 70 or at an exchange exterior thereto.

5. In a telephone exchange system, a main office, a satellite office, interoffice trunk lines between said satellite and said main office and local trunk lines at said satellite, automatic switching mechanism for effecting connection between subscribers, said mechanism including a pair of trunk finders at said satellite through one of which the line of a calling subscriber at the satellite may 80 be extended through switching mechanism to subscribers at said satellite and through the other of which said calling line may be extended by main office switching mechanism to subscribers external to the said satellite, and means at said main office operating upon the initiation of a call at said satellite for automatically selecting and completing a connection through one or the other of said trunk finders according to 85 whether the wanted subscriber is at the satellite or external thereto.

6. In a telephone exchange system, a main office, a satellite office, trunk lines extending from said satellite to said main office and other trunk lines local to said satellite, automatic switching mechanism for extending a connection from a satellite subscriber to other subscribers at said exchange, said switching mechanism including interoffice 100 trunk finders and local trunk finders at said satellite and selectors at said main office, one of said interoffice trunk finders being actuated upon the initiation of all calls at said satellite to select an interoffice trunk to 105 an idle selector, controlling devices for governing said switching mechanisms, said selector operating under the control of a controlling device at the satellite when manipulated in accordance with the number of a 110 wanted subscriber at said satellite to close a circuit, whereby means will be actuated to restore to normal said interoffice trunk finder and said selector, and complete a talking 115 circuit between the calling and called subscribers through one of said local trunk finders.

7. In a telephone exchange system, a main office, a satellite office, interoffice trunk lines from said satellite to said main office and local trunk lines at said satellite, automatic switching mechanism for effecting connection between subscribers' lines, said mechanism including local trunk finders and interoffice trunk finders at said satellite and selectors at said main exchange, controlling devices associated with said satellite for governing the operation of said switches, said interoffice trunk finders being actuated upon the initiation of all calls at the satellite to 125 130

- extend the line of the calling subscriber to a selector and said selector being actuated upon the reception of certain series of impulses from said controlling device to effect the operation of mechanism, whereby the interoffice trunk will be released and the local trunk finder will be operated to extend the line of the calling subscriber to one of said local trunks through said local trunk finder.
8. In a telephone exchange system, a main office, a satellite office, trunk lines extending from said satellite to said main office and other trunk lines local to said satellite, automatic switching mechanism for extending a connection from a satellite subscriber to other subscribers at said exchange, said switching mechanism including interoffice trunk finders and local trunk finders at said satellite and selectors at said main exchange, controlling devices for governing said switching mechanism, an interoffice trunk finder being actuated upon initiation of all calls at the satellite to select a trunk to an idle selector at the main exchange, said first selector operating under the control of a controlling device when manipulated in accordance with the number of a wanted subscriber at said satellite to close a circuit, whereby means will be operated to restore to normal the interoffice trunk finder and complete a talking circuit between the calling and called subscribers through said local trunk finder.
9. In a telephone exchange system, a main office, a satellite office, interoffice trunk lines between said satellite and said main office and local trunk lines at said satellite, automatic switching mechanism for effecting connection between subscribers, said mechanism including interoffice trunk finders and local trunk finders at said satellite and selectors at the main office, electromagnets for operating said finders, a relay for completing an initial circuit for said local trunk finder electromagnet, means operating upon energization of said local trunk finder electromagnet to interrupt the connection between a calling line and said interoffice trunk finder, means for actuating one of said interoffice trunk finders upon the initiation of a call at said satellite to select an interoffice trunk to an idle selector, controlling devices for governing the movement of said switching mechanism, and means whereby said selector operating under the control of a controlling device at the satellite when operated in accordance with the number of a wanted subscriber at said satellite will close a circuit for said relay.
10. In a telephone exchange system, a main office, a second office, interoffice trunk lines extending between said offices, other trunk lines local to said second office, and means at said main office whereby upon the initiation of all calls at said second office the subscriber's line will be connected to an interoffice trunk and whereby the subscriber's line will be connected to a local trunk only when the calling and called subscribers are at said second office.

initiation of all calls at said second office the subscriber's line will be connected to an interoffice trunk and whereby the subscriber's line will be connected to a local trunk only when the calling and called subscribers are at said second office.

11. In a telephone exchange system, a main office, a second office, interoffice trunk lines extending between said offices, other trunk lines local to said second office, switching devices at said second office for connecting the line of a calling subscriber thereto to an interoffice trunk and to a local trunk respectively, and means at said main office whereby upon the initiation of all calls at said second office the subscriber's line will be connected to an interoffice trunk and whereby the subscriber's line will be connected to the local trunk only when the calling and called subscribers are at said second office.

12. In a telephone exchange system, a plurality of offices, subscribers' lines extending to said offices, the designation of said lines being the same for all calling subscribers at the exchange, interoffice trunk lines extending between said offices, local trunk lines at said offices, an individual line switch for each line for selecting an interoffice trunk upon the initiation of all calls at one office, switching mechanism for effecting connection between subscribers, controlling devices associated with said lines for governing said switching mechanism, a second individual switch for each line and means operated under the control of said controlling devices when manipulated in accordance with the number of a wanted subscriber for completing a connection over said interoffice trunk or for releasing said interoffice trunk and effecting a connection over said second individual switch and a local trunk according to whether the wanted subscriber is located at said first or second office.

13. In a telephone exchange system, an office, a second office, interoffice trunk lines extending between said offices, local trunk lines at said second office, automatic switches for effecting connection between subscribers, said switches including individual line switches through one of which the line of a calling subscriber at said second office may be extended to subscribers at the other office, and through the other to subscribers at said second office, controlling devices associated with said second office for governing said switches, and means operated under the control of said controlling devices when manipulated in accordance with the number of the wanted subscriber for completing a connection through the required one or the other of said line switches according to whether the wanted subscriber is located at the first or second mentioned office.

14. In a telephone exchange system, a group of lines, other lines, a plurality of switches for interconnecting the lines of said group and a second plurality of switches for connecting the lines of said group to said other lines, controlling devices for governing the operation of said switches, means operated upon the initiation of a call at one of the lines of said group whereby 15
5 the controlling device thereof will be associated with one of said second plurality of switches, said switch being operated under the control of such controlling device when manipulated in accordance with the number 20
10

of a subscriber in said group of lines to close a circuit whereby means will be actuated to release said selected switch and complete a talking circuit between the calling and called lines through one of the first mentioned plurality of switches.

In witness whereof we hereunto subscribe our names this 7th day of May, A. D. 1913.

FRANK N. REEVES,
ALBEN E. LUNDELL.
